RIVETING TOOL

Sergo B. Davitow, St. Albans, N. Y.

Application July 27, 1938, Serial No. 221,636

7 Claims. (Cl. 218—19)

(Granted under the act of March 3, 1883, as
amended April 30, 1928; 370 O. G. 757)

This invention relates to a riveting tool and has for an object to provide an easily operable tool for expanding a hollow rivet which has been placed through two pieces of sheet material to secure the pieces of sheet material together. It is especially intended for use in cases where the sheet material is metal and where the ends of the sheet material are not sufficiently accessible to allow the tool to overlap one of the ends.

10 A further object of this invention is to provide a riveting tool which is hand operated and in which the operating handles are mounted as a pair of levers pivoted one upon the other and adapted to be closed toward one another during 15 the riveting operation in the same manner that the handles of a pair of pincers are operated.

A further object of this invention is to provide a hand operated riveting tool which can exert a powerful leverage to positively operate 20 the riveting mechanism of the tool.

With the foregoing and other objects in view, the invention consists in the construction, combination and arrangement of parts hereinafter described and illustrated in the drawing, in 25 which,

Fig. 1 is a partly sectional and partly elevational view of the riveting tool of this invention in closed position.

Fig. 2 is a fragmentary elevational view of the 30 riveting tool in open position.

Fig. 3 is a sectional view, similar to Fig. 2.

Fig. 4 is a sectional view on line 4—4 of Fig. 2.

Fig. 5 is an end view of the riveting end of the tool, and

Fig. 6 is a sectional view on line 6—6 of Fig. 2.

There is shown at 10 the riveting tool of this invention which includes a hollow handle lever 11 to which is pivoted at 12 another hollow handle lever 13. Stopper members 14 and 15, welded 40 or otherwise secured to the levers 11 and 13, limit the approach of the levers 11 and 13 to each other about their pivot 12. The end of the lever 11 is offset as at 16 and carries thereon a squared barrel 17 which is in axial alignment 45 with the lever 13 when the lever 13 is closed against lever 11. This barrel terminates in a nozzle 18'. Slidable within the squared barrel 17 is a squared piston 18 which may be pulled through the open end 19 of the barrel 17 by 50 means of a pair of link arms 20 which are pivoted at 21 to the handle lever 13, as shown.

The other end of the squared piston 18 is bifurcated as shown at 22, permitting a mandrel puller bottom jaw 23 to be secured between the bifurcations as at 24. Pivoted above the jaw 23, at 25, is a mandrel grip lever 26 provided with a cammed upper surface 27. The free end of the grip lever 26 presses against a compression spring 28 sunk within a well 29 formed within the 55 squared piston 18. Journaled above the rear end

of the barrel 17 between a pair of upstanding ears 30 is a lever roller 31, the roller or abutment 31 being mounted over the end of a longitudinal slot 32 along the center of the top of the squared barrel 17 through which the cammed 5 surface 27 of the grip lever 26 may extend. A mandrel 33 consisting of a rod having an enlarged head 34 is adapted to be placed through the hollow rivet 35 and through the nozzle 18' to a position between the serrations 36 on the bottom jaw 23 and the serrations 37 on the grip lever 26.

In operation, the sheets of material 38 and 39 being riveted together have the hollow rivet 35 placed therethrough in appropriate apertures 15 previously formed therein. Mandrel 33 is then placed through the hollow rivet 35 until the head 34 abuts the end of the rivet. In this position the mandrel 33 is extended through the nozzle 18' into position between the serrations 36 and 20 37 on the jaw 23 and lever 26 while the handles 11 and 13 are spread apart, thereby permitting the spring 28 to raise the lever 26 about its eccentric pivot 25, spacing the serrations sufficiently distant to permit the mandrel to enter 25 therebetween. Movement of the handles 11 and 13 toward each other through links 20 draws the piston 18 partly through the opening 19 and causes the cammed surface 27 of lever 26 to pass under the lever roller 31 and pivot the serrations 30 37 to tightly grip the mandrel 33 against the serrations 36 of the bottom jaw 23. Further approach of the handle 13 to the handle 11 pulls the complete assembly rearwardly, causing the head 34 of the mandrel 33 to approach the nozzle 35 and thus expand the rivet 35 to the riveted position shown at 40, the stops 14 and 15 limiting the approach of the levers 11 and 13 to the proper distance so that the movement of the mandrel head 34 is stopped when the rivet 35 has been 40 properly expanded to the position 40. Moving the handle levers 11 and 13 apart reverses the operation in pushing the mandrel 33 partly out of the now expanded rivet 40, allowing the mandrel 33 to be withdrawn and replaced in a new 45 rivet for further operation. Alternately, the mandrel 33 may be an inexpensive nail of suitable size, which may be discarded and replaced at each riveting operation.

It will be noted from Fig. 1 of the drawing 50 that when the handles 11 and 13 approach their closed position, that because of the leverage, the pull exerted on the mandrel 33 is very great. The purpose of this arrangement is not only to provide the required pulling force on the mandrel 33 to effect the desired expanding of the rivet, but also, if desired, when using a mandrel having a tapered head shown in the drawing to pull the head 34 of the mandrel entirely through the rivet opening. The mandrel head which is 55 60

slightly deformed in this operation serves to expand the shank of the rivet sufficiently to form a secure fastening.

Other modifications and changes in the proportions and arrangements of the parts may be made by those skilled in the art without departing from the nature of the invention, within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

1. A riveting tool for pulling a mandrel having a body portion adapted to pass through a hollow rivet having a head at one end and being headless at the other end, which headless end is to be expanded into an out-turned flange by a head portion on the mandrel larger than the hollow rivet and being adapted to expand the headless end portion of the rivet when the mandrel is pulled into the rivet while maintaining the head of the rivet stationary relative to the tool, said tool comprising means for engaging the body portion of the mandrel for pulling the same into the rivet comprising a barrel, a piston movable within said barrel, a serrated jaw fixed in said piston, a cammed serrated jaw eccentrically pivoted in said piston, means for pulling said piston out of said barrel and other means for simultaneously camming said cammed jaw into engagement with said mandrel body to thereby expand the rivet.

2. A riveting tool for pulling a mandrel having a body portion adapted to pass through a hollow rivet having a head at one end and being headless at the other end, which headless end is to be expanded into an out-turned flange by a head portion on the mandrel larger than the hollow rivet and being adapted to expand the headless end portion of the rivet when the mandrel is pulled into the rivet while maintaining the head of the rivet stationary relative to the tool, said tool comprising means for engaging the body portion of the mandrel for pulling the same into the rivet comprising a barrel, a piston movable within said barrel, a serrated jaw fixed in said piston, a cammed serrated jaw eccentrically pivoted in said piston, means for pulling said piston out of said barrel and other means for simultaneously camming said cammed jaw into engagement with said mandrel body to thereby expand the rivet, said pulling means comprising a handle lever on which said barrel is mounted, a second handle lever pivoted to said first handle lever, means linking said piston to said second handle lever, and a cam cooperating roller journaled on said barrel in the path of said cammed lever adapted to press and hold said cammed lever in mandrel gripping and holding position as the piston is drawn along under the roller.

3. A riveting tool for pulling a mandrel having a body portion adapted to pass through a hollow rivet having a head at one end and being headless at the other end, which headless end is to be expanded into an out-turned flange by a head portion on the mandrel larger than the hollow rivet and being adapted to expand the headless end portion of the rivet when the mandrel is pulled into the rivet while maintaining the head of the rivet stationary relative to the tool, said tool comprising means for engaging the body portion of the mandrel for pulling the same into the rivet comprising a barrel, a piston movable within said barrel, a serrated jaw fixed in said piston, a cammed serrated jaw eccentrically pivoted

oted in said piston, means for pulling said piston out of said barrel and other means for simultaneously camming said cammed jaw into engagement with said mandrel body to thereby expand the rivet, said pulling means comprising a handle lever on which said barrel is mounted, a second handle lever pivoted to said first handle lever, means linking said piston to said second handle lever, and a cam cooperating roller journaled on said barrel in the path of said cammed lever adapted to press and hold said cammed lever in mandrel gripping and holding position as the piston is drawn along under the roller.

4. In a device for affixing a tubular rivet by drawing a mandrel through it, said mandrel being formed as a rod with an enlarged head adapted to upset a headless end of a rivet to affix it, a casing, an axially sliding member supported by said casing and having a fixed clamping wall and a clamping part, means operating on sliding movement of said member to cause said part to engage said mandrel and to clamp the mandrel against said wall, means to disengage said mandrel to release the same, a handle fixed to said casing, a second handle mounted in pivotal relation to the first named handle, and a connection between said second named handle and said member for sliding said member.

5. In a device for affixing a tubular rivet by drawing a mandrel through it, said mandrel having an enlarged head adapted to upset the headless end of the rivet to affix it, an axially reciprocating member having mandrel clamping jaws, means to cause the jaws to grip the mandrel during the sliding movement of the member in one direction and to hold the mandrel gripped while it is moved into clamping affixing engagement with the rivet and on movement in the other direction to maintain the gripping engagement with the mandrel, and means operating after a predetermined movement of said member in said other direction to release said mandrel for withdrawal from the device.

6. In a device for affixing a tubular rivet by drawing a mandrel through it, said mandrel having an enlarged head adapted to upset the headless end of the rivet to affix it, an axially reciprocating member having mandrel clamping jaws, means to cause the jaws to grip the mandrel during the sliding movement of the member in one direction and to hold the mandrel gripped while it is moved into clamping affixing engagement with the rivet and on movement in the other direction to maintain the gripping engagement with the mandrel, and resilient means operating after a predetermined movement of said member in said other direction to release said mandrel for withdrawal from the device.

7. In a device for affixing a tubular rivet by drawing a mandrel through it, said mandrel having an enlarged head adapted to upset a headless end of a rivet to affix it, a casing, an axially sliding member in said casing having mandrel clamping jaws, one of which is formed with a cam surface, an abutment on the casing in contact with which said surface moves on motion of said member in one direction whereby said jaw is moved to clamp the mandrel and maintain it clamped during continued movement in said direction and means for releasing said jaw on movement of said member in the opposite direction.
